UNITED STATES PATENT OFFICE.

CHARLES E. ADAMSON, OF MARION, INDIANA, ASSIGNOR TO ADDRESSOGRAPH COMPANY, OF CHICAGO, ILLINOIS, A CORPORATION OF ILLINOIS.

DUPLICATING-MACHINE.

1,220,583.

Specification of Letters Patent.

Patented Mar. 27, 1917.

Application filed June 14, 1909, Serial No. 502,040. Renewed February 2, 1917. Serial No. 146,260.

To all whom it may concern:

Be it known that I, CHARLES E. ADAMSON, a citizen of the United States, residing at Marion, in the county of Grant and State 5 of Indiana, have invented certain new and useful Improvements in Duplicating-Machines, of which the following is a specification.

My invention relates to improvements in 10 duplicating-machines, such as are used for imitating typewritten-letter work.

The primary object of my invention is the production of a simple and inexpensive machine of this character which possesses all 15 the advantages and the perfect printing qualities of complicated and expensive machines.

Another object of my invention is the provision of a tilting-carriage arranged for 20 reciprocating movement over a type-bed and so constructed that by means of its tilting movement, the impression-roller may be moved toward and from the type-form on said bed so that in the movement of said 25 carriage in one direction, the impression-roller is in contact with the sheet of paper placed upon the ribbon-covered type-form and during the movement of said roller in its opposite or return direction, said roller 30 is elevated to travel in a higher plane, out of contact with said sheet of paper.

Another object of my invention is to so arrange and support the impression-carriage that during its forward movement, 35 the pressure exerted by the operator in moving it forward, will naturally tend to force the impression-roller against the ribbon-covered type-form, and in drawing the said carriage backward, will naturally tend 40 to move said impression-roller upward, away from the type-form, thereby obtaining the imprint of the type-form upon a sheet of paper laid upon the inked-ribbon during 45 the movement of said carriage in one direction only.

A still further object of my invention is to provide the carriage with a pair of guide-rollers traveling and confined in a pair of 50 guide grooves or tracks and serving as a combined pivot and rollers for the carriage, so that the latter may be moved back and forth and tilted on said rollers at any point within range of its movement, thus enabling 55 post cards, letter-heads of different sizes, or any other matter to be printed upon with-

out compelling the operator to move the impression-roller the full length of the type-bed.

With these and other objects in view my invention consists in a type-bed, suitable 60 guide-grooves or tracks, and a printing-member movable lengthwise of said type-bed and arranged to be tilted so as to raise or lower the impression-element, as may be desired; and it also consists in the construction, arrangement, and combination of parts 65 to be hereinafter described and more particularly pointed out in the subjoined claims.

In the drawings,—

Figure 1 is a side elevation of a duplicating-machine constructed according to my 70 invention.

Fig. 2 is a plan view of the same.

Fig. 3 is a longitudinal section taken on 75 line 3—3, Fig. 2.

Fig. 4 is a transverse section taken on line 4—4, Fig. 2.

Fig. 5 is an enlarged transverse section 80 through the impression-carriage, taken on line 5—5, Fig. 1, all other parts of the machine through which said line passes being omitted.

Fig. 6 is an enlarged section taken on line 85 6—6, Fig. 4, the impression-carriage being shown in its normal or printing position, in which position it is forced forward by the operator over the type-form.

Fig. 7 is a similar view showing the impression-carriage tilted so as to elevate the 90 impression-roller; this being the position of the carriage when the operator draws the same backward.

Fig. 8 is an enlarged section through one 95 of the ends of the impression-carriage, taken on line 8—8, Fig. 2.

Fig. 9 is an enlarged transverse section taken on line 9—9, of Fig. 2.

Referring now to the drawings in detail, like letters of reference refer to like parts in 100 the several figures.

The reference letter A designates a support, preferably formed of wood, and provided centrally with a receptacle *a* in which the sheets of paper after being printed upon 105 this improved machine, may be placed. The machine rests upon said support and comprises a frame B having a flat bed C and an upstanding flange D at each side; the edges of said flanges being round at their rear 110

ends, as at *d*, for a purpose to appear hereinafter.

Secured to the upper edges of said flanges are retainer-strips *E*; each strip being curved at its rear end to conform to the curved end of the flange *D* to which it is secured and at its other end it is bent at a right-angle, as at *e*. Said retainer-strips overhang the inner faces of the flanges *D* and provide guide-grooves or tracks *F* closed at their rear ends by the curved portions of said strips, as at *e*¹, and at their other ends by the bent portions *e* of said strips. Each of said retainer-strips is notched out at its front end, as at *G*.

Set upon the type-bed is a chase *H* held against lateral movement by chase-retainers *h*, *h*¹ arranged lengthwise on the type-bed and separated from the guide-grooves or tracks *F* by intervening spaces *I*. The chase retainers *h*, *h*¹, consist of angle-plates screwed or otherwise fastened to the type-bed and the chase-retainer *h*¹ has a friction-strip *J* and a securing-strip *j* by means of which latter said friction-strip is held to said chase-retainer; screws or other suitable fastening-means being provided for the purpose.

K are ribbon-rollers arranged at opposite ends of the type-bed, from one of which an inked-ribbon *K*¹ is to be paid out to be wound upon the other; and for the purpose of accomplishing this automatically, a pawl and ratchet-feed *L* is provided, said feed being of any common construction.

M designates the impression-carriage which is adapted to be reciprocated on the frame and it comprises a casting having a cross-bar *m* connecting side-members *m*¹; said side-members being notched at their front ends, as at *m*² to receive bearing-boxes *N* in which are held opposite ends of a spindle *n* having an impression-roller *n*¹ rotatable thereon. Between one end of said impression-roller and the adjacent side-member of the carriage, a distance-sleeve *n*² is placed which surrounds the spindle *n*. Each of the side-members of the impression-carriage is provided with vertical bores *n*³ extending from its lower edge to the notch formed therein and the lower ends of said bores are threaded and receive threaded plugs *O*, between the upper ends of which plugs and the bearing-boxes, spiral springs *o* are interposed. Said springs serve to cushion the impression-roller in its travel over the sheet of paper laid upon the ribbon-covered type-form so that the impression-carriage will move easily over said type-form and so that an even impression will be obtained on the paper. For the purpose of holding the impression-roller with the desired pressure against the ribbon-covered type-form, adjusting-screws *P* are arranged at opposite ends of the impression-carriage;

said screws being threaded through the carriage above the notches *m*² therein and having reduced lower ends to provide shoulders *p* which bear against the upper edges of the bearing-boxes while the reduced lower ends thereof pass through bores *p*¹ in said bearing-boxes and enter bores *p*² in the side members of the carriage beneath said boxes. The extent to which the bearing-boxes may be elevated by the springs *o* is therefore governed by the shoulders *p* on said adjusting-screws and said boxes are held against removal by the lower reduced ends of said screws. When said adjusting-screws are adjusted to hold the bearing-boxes in the desired position so as to cause the impression-roller to move over the ribbon-covered type-form with proper pressure, they are held in adjusted position by means of lock-nuts *p*³.

The impression-carriage is provided with a rearwardly extending handle *Q* to be grasped by the operator in moving the carriage back and forth on the frame. Said carriage is also provided with two pairs of guide-rollers or wheels *R*, *R*¹, one of each pair being at each end. The wheels *R* are of greater diameter than the wheels *R*¹ and approximately correspond in size to the height of the guide-grooves *F*. Said wheels are rotatably held on stub axles *r* secured in the ends of the carriage, the axles of the wheels *R* being coincident, also those of the wheels *R*¹, so that the carriage will travel in a straight line without binding.

The wheels *R* serve as pivots or fulcrums on which the carriage may be tilted, as shown in Fig. 7, and they are arranged in a vertical plane to one side but preferably in advance of the axis of the impression-roller so that when the carriage is tilted, said impression-roller is slightly elevated to relieve the same of pressure, as shown in dotted lines in Fig. 7. The wheels *R*¹, by reason of their being of smaller diameter, permit the carriage to be tilted and in addition to serving as traction-wheels, they also serve as stops to limit the extent to which the carriage may be tilted.

As the handle of the carriage is in a plane in rear of the impression-roller and the rollers *R* are in a plane to one side or in advance of the axis of the impression-roller, the tendency in forcing the carriage forward on the frame of the machine, is to bear down upon the handle and in so doing, cause the impression-roller to be forced against the sheet of paper placed upon the ribbon-covered type-form, and during this movement of the carriage, the smaller guide-wheels *R*¹ travel in contact with the lower walls of the guide-grooves *F*. During the return movement of the carriage, the tendency is to draw upward on the handle while drawing the carriage backward, thus caus-

ing said carriage to be tilted until the small guide-wheels R^1 strike the retainer-strips or upper walls of said guide-grooves, thus causing the impression-roller to be moved away 5 from the imprinted paper. It is to be noted that the carriage tilts on a center beneath the axis of the impression roller and within the guide grooves F .

Between the chase H and the chase-retainer h , a paper-gage S is inserted which has at one end an inwardly projecting lip s that extends over the adjacent side of the chase and acts as a stop for the end edge of the paper. This gage may be moved lengthwise 15 between the chase-retainer and the chase so as to bring said stop at any desired point.

A finger-guard T is provided which is angular in cross-section to provide a vertical securing-member t adapted to be clamped 20 between the securing-strip j and the chase and a slightly inclined guard-member t^1 extending inward over the marginal portion of the inked-ribbon so that the sheets of paper placed upon the latter will extend 25 over said finger-guard with the marginal portion of the paper separated from said guard by an intervening space t^2 , which permits of inserting the finger beneath the 30 extending portion of the paper so that it may be easily taken hold of in order to remove it, without possibility of taking hold of the inked-ribbon underneath the paper. This guard assures a quick removal of the 35 paper, and as the speed of the machine is governed entirely by the dexterity of the operator in placing the sheets of paper upon the ribbon-covered type-form and removing the same therefrom, the importance of 40 said guard will be readily understood.

The notches G formed in the front ends of the retainer-strips E permit the removal of the impression-carriage from the frame; it being simply necessary to force the carriage forward until the guide-wheels R are 45 positioned underneath said notches, after which, upon tilting said carriage, said rollers may be passed upward through said notches and the carriage then forced forward 50 until the pair of smaller rollers R^1 are in line with said notches. The entire carriage can then be lifted from the frame.

The pawl and ratchet-feed L at the rear end of the frame is arranged to be actuated 55 by the impression-carriage so that with each rearward movement of said carriage, the inked-ribbon is fed over the type-form in a manner common to machines of this type. By curving the rear ends of the retainer-strips E , they act as stops to limit the rearward movement of the carriage. The smaller 60 pair of guide-wheels R^1 , which travel along the under side of the retainer-strips during the rearward movement, roll in contact with 65 said curved rear ends and as the operator

draws upward on the handle of the impression-carriage while pulling the same backward, it checks the further rearward movement of the carriage in a noiseless manner.

Having thus described my invention, what 70 I claim is,—

1. A duplicating machine comprising two members, one of said members having a type form provided with guides and the other being movable and having coöperating 75 guides by means of which it is guided for movement in the guides of said first-mentioned member and also for bodily swinging movement, and an impression element carried by said movable member and adapted to be moved toward and from said type form when swinging said movable member.

2. The combination with a bed having a printing form thereon, of a carriage supported directly by said bed for movement 85 relative thereto and having guide wheels thereon serving to guide it in its movements in lines conforming to the surface of said printing-form, said carriage being supported to tilt bodily on some of said guide-wheels 90 and an impression roller rotatable in said carriage, the whole being arranged to bring said impression-roller into contact with said printing-form or to move the same away from said form when bodily tilting said 95 carriage.

3. The combination with a frame having a printing-form thereon, of a carriage having guide means at its sides engaging said frame and adapted to be tilted bodily with 100 said guide-means serving as pivotal points, and an impression-element supported by said carriage, and adapted to be moved toward or from said printing-form when bodily tilting said carriage.

4. The combination with a frame having a printing form thereon and provided with guide-means, of an impression-carriage, and an impression-roller rotatable in said carriage, said carriage having coöperating 110 guide-means comprising a pair of aligned rollers and said impression-carriage being capable of tilting bodily with said guide-means as pivotal centers so as to move said impression-roller into and out of printing 115 position.

5. The combination with a bed bearing a type form, of a carriage supported directly by said bed and having an impression roller held against movement, other than rotary, 120 independent of said carriage, said carriage being arranged for bodily reciprocating and swinging movement, said carriage being also adapted for hand operation and arranged to swing toward the type form when starting 125 its movement in one direction and away from said type form when starting its movement in its opposite direction.

6. The combination of a frame having a printing-form thereon, of a carriage guided 130

for movement on said frame and having an impression-roller, a pair of guide-wheels in a plane in advance of the axis of said impression-roller and a second pair of guide-rollers in a plane in rear of said axis, said second pair of rollers being smaller than the first-mentioned pair so as to permit the carriage to be tilted for the purpose of bringing the impression-roller into or out of printing position.

7. The combination with a frame having guide-grooves and a printing-form, of an impression-carriage including an impression-roller and having means for bodily guiding it in said guide-grooves so arranged that it may be tilted bodily in said grooves to move said impression-roller into or out of printing position.

8. The combination with a frame having guide grooves whose upper walls at least are curved downward at one of their ends, of an impression carriage having an impression roller rotatably applied thereto, said carriage having a pair of guide wheels in a plane to one side of the axis of said impression roller of a diameter to fit said guide grooves and a second pair of guide rollers of smaller diameter at the other side of said plane riding in said grooves and adapted to contact with said curved wall as said carriage approaches the end of its movement in one direction.

9. The combination with a frame having a printing-form and a pair of guide-grooves, of an impression carriage arranged transversely on said frame and including an impression-roller, said carriage having a pair of guide-wheels in a plane in advance of the axis of said impression-roller of a diameter to fit said guide-grooves and a second pair of guide-rollers of smaller diameter riding in said grooves and permitting the carriage to be tilted so as to bring the impression-roller into and out of printing position.

45 10. The combination with a frame having a printing form and a pair of guide grooves, of an impression carriage arranged transversely on said frame and including an impression roller, said carriage having a pair 50 of guide wheels in a plane to one side of the axis of said impression roller and a second pair of guide rollers of a smaller diameter in said grooves at the other side of said plane and permitting the carriage to be tilted so as to bring the impression rollers into and out of printing position.

55 11. A printing-carriage for duplicating machines comprising a frame having a cross-bar connecting two end-members, said end-members having notches, a threaded bore extending through said end-members above each notch and a smooth bore extending into each of said end-members from the bottom

of said notches, bearing-boxes in said notches having bores extending therethrough coincident with the bores in said end-members, adjusting-screws threaded through said threaded bores and having reduced lower ends passing through the bores of said bearing-boxes and entering the smooth bores in said end-members, said adjusting-screws having shoulders bearing against the upper sides of said bearing-boxes, an impression-roller mounted in said bearing-boxes, and coil-springs set into said end-members and bearing against the undersides of said bearing-boxes.

12. The combination with a frame having a flat-bed, a printing-form upon said bed and retainers also upon said bed adapted to hold said form in position, of an inked-ribbon movable over said form onto which a sheet of paper to be printed is to be placed, an impression element movable over said ribbon-covered printing-form, and a finger-guard comprising a sheet of metal bent into angular shape in cross-section and clamped between said form and one of said retainers, said guard extending over the marginal portion of said inked-ribbon.

13. The combination with a bed bearing a type form, a carriage having a handle immovably fixed thereto adapted to be grasped to reciprocate the carriage in a plane conforming to said type form, said carriage being adapted to be pushed in one direction and pulled in its opposite direction, and an impression element carried by said carriage and adapted to be moved toward the type form when the carriage is commencing its movement in one direction and to be moved away from the type form when said carriage is commencing its movement in its opposite direction.

14. The combination with a bed bearing a type form, of a carriage comprising a rigid structure having guide means engaging said bed to permit of reciprocating and pivotal movement of said carriage, and an impression element journaled in said carriage movable toward and from said type form when swinging said carriage.

15. The combination with a bed having a printing form thereon, of a carriage having combined guide and pivot rollers, and an impression members so related to said rollers that upon swinging said carriage the impression member is moved toward and from said type form.

In testimony whereof, I have affixed my signature in the presence of two subscribing witnesses.

CHARLES E. ADAMSON.
